UNITED STATES PATENT OFFICE.

ABRAHAM A. SHOBE AND WILLIAM EMBLEY, OF JERSEYVILLE, ILLINOIS.

ELECTRIC-RAILWAY CROSSING.

SPECIFICATION forming part of Letters Patent No. 761,549, dated May 31, 1904.

Application filed September 26, 1903. Serial No. 174,810. (No model.)

To all whom it may concern:

Be it known that we, ABRAHAM A. SHOBE and WILLIAM EMBLEY, citizens of the United States, residing at Jerseyville, in the county 5 of Jersey and State of Illinois, have invented a new and useful Electric-Railway Crossing, of which the following is a specification.

This invention relates to certain improvements in electric railways of that general class 10 in which the conductors are arranged in underground conduits.

The principal object of the invention is to provide an improved arrangement of the current-conductors at points where railway-lines 15 intersect, so that the circuits of the lines may be kept independent and short-circuiting prevented.

A still further object of the invention is to provide a novel form of support for the intersecting conductors and to so arrange the connection as to permit longitudinal expansion 20 and contraction of the conductors.

With these and other objects in view, as will more fully hereinafter appear, the invention 25 consists in the novel construction and arrangement of parts hereinafter described, illustrated in the accompanying drawings, and particularly pointed out in the appended claims, it being understood that various 30 changes in the form, proportions, size, and minor details of the structure may be made without departing from the spirit or sacrificing any of the advantages of the invention.

In the accompanying drawings, Figure 1 is 35 a sectional elevation of an electric-railway crossing constructed in accordance with the invention. Fig. 2 is a plan view of the same. Fig. 3 is a transverse sectional elevation of the crossing on the line 3-3 of Fig. 2. Fig. 4 is a detail perspective view illustrating the 40 manner in which the conductors cross each other, the supports and the insulating material being removed. Fig. 5 is a similar view of the cover of the support and insulator- 45 holder detached. Fig. 6 is a similar view showing the supporting-plate for the box or crossing. Fig. 7 is a transverse sectional elevation of a portion of the device on the line 7-7 of Fig. 3.

50 Similar numerals of reference are employed

to indicate corresponding parts throughout the several figures of the drawings.

In the drawings, 1 designates a portion of a vertical wall of an underground conduit as seen at the intersection of two roads, the positive conductors being indicated at 2 and the negative conductors at 3. At the intersecting point is arranged a rectangular frame 4 in the form of an angle-bar in cross-section, the vertical web of the frame being bolted or riveted to the vertical wall of the conduit. This frame serves as a support for a horizontal plate 5, having a centrally-disposed drainage-opening 6 and a plurality of openings 7, forming recesses through which accumulated 65 water may pass to the bottom of the conduit. On this plate rests a box or crossing 8, following the contour of the lower plate 5 and substantially rectangular in form. This box has suitable outer walls 9 and is provided with 70 inner walls 10, following the contour of the central drainage-opening 6 of the plate. This box serves to contain an insulating material 12 and is covered by a top piece 13 of approximately the same shape as the box, the 75 upper surface of said top piece being provided with inclined beveled portions around the several openings and recesses in order to more effectually shed the water.

The positive conductor 2 is in the form of 80 a T-rail, as shown in the drawings, and terminates at points adjacent to the supporting-plate of the frame 4, and the ends of the alining and spaced sections of the conductor are connected by a bar 14, having slotted end portions so arranged as to embrace the horizontal web of the positive conductors 2. The connecting-bar 14 is preferably formed of 85 copper or similar material of good conductive properties, and its upper edges after embracing the edge portions of the main conductor are turned downward and are held from lateral play by means of non-conducting supports 17. The supports 17 are preferably formed of 90 wood and are extended from end to end of the road. Each support comprises a pair of bars having grooves 18 in their adjacent walls, these grooves serving to receive a T-shaped lower head of a clip 19, that is riveted or otherwise permanently secured to the vertical 95 100

web of the main conductor 2, the clips being arranged at intervals and permitting free longitudinal movement of the main conductor when expansion or contraction occurs from 5 thermal changes. The end clip serves to hold both the main conductor and the connecting-bar in proper relative position, while the open end of the bar will permit of the necessary longitudinal movement of said main conductor.

10. The bar is introduced through the top member 13 and passes through the insulating material in the box and thence upward to an opening in the opposite side of the top member to its connection with the opposite T-shaped conductor. The construction and arrangement of the crossing part of the bar are similar to that already described, the crossing-bars arranged within the box being disposed in different horizontal planes and protected by the insulating material.

15. The negative or return conductors are T-shaped in cross-section and their vertical webs terminate outside the box or casing, the horizontal webs being bent downward below the general level of the conductors and extended through suitable openings in the box-cover, being thence passed through the insulating material, the conductors being disposed at different levels, so as not to interfere with 20 each other.

25. Having thus described the invention, what is claimed is—

1. In an electric-railway crossing, the combination with conductors arranged in intersecting lines, of a box or casing containing insulating material disposed at the point of intersection, and overlapping strips of conducting material arranged in said box or casing and connected to said conductors.

30. 2. In an electric-railway-crossing connection, a box or casing, insulating material contained therein, and crossing and overlapping conducting members supported by the insulating material and having their ends projecting from said box or casing.

35. 3. In an electric-railway crossing, a box or casing having drainage openings or recesses, insulating material contained in the box or casing, overlapping conducting members protected by the insulating material and having their ends projecting from the box, and a cover having beveled or inclined portions forming watersheds leading to said drainage openings or recesses.

40. 4. In an electric-railway crossing, a box or casing having a central opening and provided with a plurality of marginal recesses, insulat-

ing material disposed within said box or casing, a cover-plate having inclined or beveled portions for directing water to the central opening and the several recesses, and conducting members extending through the insulating material and having their opposite ends protruding from the box or casing.

45. 5. In an electric-railway crossing, the combination with metallic conductors, of a casing containing insulating material, and a conducting-bar having its intermediate portion embedded in the insulating material, the opposite ends of said bar being open and embracing the main conductors to thereby permit free longitudinal movement of the latter.

50. 6. In an electric-railway crossing, the combination with metallic conductors, of a casing containing insulating material, a conducting-bar having its opposite end portion opened and embracing the ends of the main conductors, and means for preventing lateral play of the end portion of said bar.

55. 7. In an electric-railway crossing, the combination with a pair of slotted supporting-bars formed of non-conducting material, a main conductor of T-shape form in cross-section, a clip connected to the vertical web of the T and having a T-shaped head portion adapted to the grooves of the support, a cross-box containing insulating material, and a conducting-bar having its intermediate portion embedded in insulating material, the end portion of said bar being opened to embrace the horizontal web of the T-shaped bar, the edges of said conductor being turned down or flanged to fit between the two portions of the support.

60. 8. In an electric-railway crossing, a conduit-supporting frame, a plate carried thereby and provided with a central opening and a plurality of marginal recesses, a box or casing having a corresponding opening and corresponding recesses, said box or casing being supported by the plate, a cover carried by the box or casing and also provided with an opening and recesses, insulating material disposed within the box or casing, and conducting members buried in the insulating material and overlapping members having their opposite ends protruding from the box or casing.

65. In testimony that we claim the foregoing as our own we have hereto affixed our signatures in the presence of two witnesses.

ABRAHAM A. SHOBE
WILLIAM EMBLEY.
